(57) CLAIM

The ornamental design for display screen or portion thereof having a graphical user interface for displaying an animated wait time visualization, as shown and described.

DESCRIPTION

FIG. 1 is a front view of a first embodiment of a display screen or portion thereof having a graphical user interface for displaying an animated wait time visualization showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a eighth image thereof;

FIG. 9 is a front view of a ninth image thereof;

FIG. 10 is a front view of a tenth image thereof;

FIG. 11 is a front view of a second embodiment of a display screen or portion thereof having a graphical user interface for displaying an animated wait time visualization showing our new design;

FIG. 12 is a front view of a second image thereof;

FIG. 13 is a front view of a third image thereof;

FIG. 14 is a front view of a fourth image thereof;

FIG. 15 is a front view of a fifth image thereof;

FIG. 16 is a front view of a sixth image thereof;

FIG. 17 is a front view of a seventh image thereof;

FIG. 18 is a front view of a eighth image thereof;

FIG. 19 is a front view of a ninth image thereof;

FIG. 20 is a front view of a tenth image thereof;

FIG. 21 is a front view of a third embodiment of a display screen or portion thereof having a graphical user interface for displaying an animated wait time visualization showing our new design;

FIG. 22 is a front view of a second image thereof;

FIG. 23 is a front view of a third image thereof;

FIG. 24 is a front view of a fourth image thereof;

FIG. 25 is a front view of a fifth image thereof;

FIG. 26 is a front view of a sixth image thereof;

FIG. 27 is a front view of a seventh image thereof;

FIG. 28 is a front view of a eighth image thereof;
FIG. 29 is a front view of a ninth image thereof;
FIG. 30 is a front view of a tenth image thereof;
FIG. 31 is a front view of a fourth embodiment of a display screen or portion thereof having a graphical user interface for displaying an animated wait time visualization showing our new design;
FIG. 32 is a front view of a second image thereof;
FIG. 33 is a front view of a third image thereof;
FIG. 34 is a front view of a fourth image thereof;
FIG. 35 is a front view of a fifth image thereof;
FIG. 36 is a front view of a sixth image thereof;
FIG. 37 is a front view of a seventh image thereof;
FIG. 38 is a front view of a eighth image thereof;
FIG. 39 is a front view of a ninth image thereof; and,
FIG. 40 is a front view of a tenth image thereof.
The appearance of the animated design transitions sequentially between the images shown in FIGS. 1-10, 11-20, 21-30, and 31-30.
For each embodiment, the process or period in which one image transitions to another in each of the embodiments forms no part of the claimed design.
The broken lines showing a device form no part of the claimed design. The broken lines showing a display screen form no part of the claimed design. All other broken lines show portions of the graphical user interface and form no part of the claimed design.
